LATCHING MECHANISM FOR SWITCH AND
LOCK MOVEMENTSWilliam R. Gracey, Jr., Swissvale, Pa., assignor to
Westinghouse Air Brake Company, a corpora-
tion of Pennsylvania

Application September 30, 1950, Serial No. 187,770

5 Claims. (Cl. 246—253)

1

My invention relates to railway switch operating mechanisms, and particularly to improvements in the latching mechanism shown and described in Letters Patent of the United States No. 2,184,870 granted to Herbert L. Bone and Kenneth J. J. McGowan on December 26, 1939, for Railway Switch Operating Mechanisms.

In the aforesaid patent, the latching mechanism comprises a spring biased pivoted point detector lever cooperating with the point detector rod secured to the switch points of the switch. The point detector lever cooperates with a rocker arm of the circuit controller provided for the switch operating mechanism. Integral with the point detector lever is a latch arm having a latch dog which cooperates with a spring biased pivoted latching member. The parts are so proportioned and adjusted that when the switch is trailed, the movement of the switch point away from the stock rail will cause the point detector rod to move, to pivot the point detector lever. The rotation of the point detector lever rotates the rocker arm of the circuit controller to close signal control contacts which when closed will set the signals governing traffic over the switch to "stop." The rotation of the point detector lever also rotates the latch arm so that the latch dog enters the notch of the latching member to hold the point detector lever in its rotated position. Consequently, the rocker arm of the circuit controller is held in its rotated position to hold the signal control contacts closed.

In order to clear the signal for traffic moving over the trailed switch, the latching member may be reset by hand, or the switch operating mechanism may be operated to move the switch to its opposite position, in which event a cam dog carried by the lock bar will engage a cam arm on the latching member to release the latching member.

Under conditions of operation where the switch and lock movement is subject to excessive vibration due to the pounding on the rails of a passing train over the switch, a longitudinal load is sometimes suddenly applied along the axis of the point detector bar which is transmitted to the lever latch arm. The lever latch arm is thus displaced downwardly to permit the latch dog to enter the notch of the latching member and a false latchout occurs. While the latching device may be reset by operating the movement to reverse the switch points, the false latchouts cause some delay and inconvenience.

It is therefore an object of my invention to provide a novel self-restoring latching device

2

for a switch and lock movement in which false latchouts due to excessive vibration and shock are substantially reduced.

In carrying out my invention I provide the latching member of the latching device with a cam surface which cooperates with the latching dog carried by the lever latch arm. When the lever latch arm is suddenly displaced in the manner hereinbefore indicated, the latching dog will abut the camming surface to throw the latching member out of the way to keep the latching dog from engaging the latching member notch. As the displacement and return of the lever latch arm is very rapid when a shock load occurs, sufficient time is provided in throwing the latching member out of the way to permit the lever latch arm to return to its normal position before the latching member returns to its normal position. Thus with the return of the lever latch arm to its normal position before the latching member, false latchouts will be prevented.

I shall describe two forms of latching mechanisms embodying my invention, and shall then point out the novel features thereof in claims.

In the accompanying drawings, Fig. 1 is a view showing a railway switch operated by a switch operating mechanism in which my novel latching mechanism is incorporated. Fig. 2 is a vertical longitudinal sectional view of the switch operating mechanism shown in Fig. 1. Fig. 3 is a sectional view on an enlarged scale taken substantially along the line III—III of Fig. 2. Fig. 4 is a top plan view of the circuit controller end of the switch operating mechanism with the cover removed. Fig. 5 is an enlarged elevational view of the latching mechanism embodying my invention showing the latching members in their unlatched positions, while Fig. 6 is an enlarged elevational view of a second embodiment of my latching mechanism.

Similar reference characters refer to similar parts in each of the several views.

Referring to Fig. 1, the reference character A designates a railway switch comprising two fixed rails 1 and 1a and two movable rails or switch points 2 and 2a. The fixed rails are laid on tie plates 3 and are secured to crossties 4 in the usual manner. The switch points 2 and 2a are fastened together by means of a front rod 5 and a head rod 6, and may be moved into a normal or reverse position by means of a throw rod 7 which is connected to the head rod by way of a switch basket 8. When the switch A occupies its normal position as illustrated in Fig. 1, the switch point 2 engages the fixed rail 1

while the switch point $2a$ is spaced from the fixed rail $1a$. When the switch A is reversed, the switch point $2a$ engages the fixed rail $1a$ while the switch point 2 is spaced from the fixed rail 1 .

Secured to the elongated crossties 4 adjacent the outer side of rail 1 is a switch and lock movement B more fully described in the aforesaid Letters Patent of the United States No. 2,184,870. In Figs. 2, 3, and 4 of the drawings, sufficient details of the switch and lock movement are illustrated which, when considered with the description hereinafter given, will be adequate for an understanding of the operation of the particular movement.

A suitable casing 9 encloses the operating parts of the movement B, a readily removable cover 10 giving access to the parts. Located within the casing 9 is a motion plate 11 adapted to slide longitudinally in a direction parallel to the track by means of guide rollers 12 secured to the underside of the motion plate and cooperating with suitable guideways 13 provided on the bottom wall of the casing 9 . The upper surface of the motion plate is formed with rack teeth 14 which mesh with a segment gear 15 mounted on a square shaft 16 . The ends of the shaft 16 are mounted in bearing sleeves 17 and $17a$ journaled in bosses 18 formed in the sidewalls of the casing 9 . Secured to an outer end of the shaft 16 as by a bolt 19 is a hand-throw lever 20 which serves as a means for reciprocating the motion plate 11 from one extreme position to the other.

Means are now provided for moving the switch points 2 and $2a$ into their normal and reverse positions and locking the points in their extreme position upon movement of the motion plate 11 from its one extreme position to its other extreme position. To this end a roller 21 is secured to the underside of the motion plate at a point intermediate the rollers 12 . The roller 21 cooperates with cam faces (not illustrated) formed on an escapement crank 22 . The escapement crank 22 is formed integrally with the upper end of a vertical switch actuating shaft 23 suitably journaled in bearings 24 and 25 formed respectively in the bottom of casing 9 and a depending stirrup 26 provided on the underside of the casing. Secured to the shaft 23 is a switch operating arm 27 , the end of which is pivotally connected (not shown) to the free end of the throw rod 7 .

Operatively connected to the motion plate 11 by means of a stud 28 is a lock bar 29 extending longitudinally of the casing directly above the motion plate. The lock bar 29 is slidably mounted at one end in a guide plate 30 secured to the end of the casing and at the other end in a guideway 31 formed in a frame 32 bolted to the casing adjacent the left-hand end thereof. The stud 28 is secured to the lock bar and extends into a transversely extending slot $11a$ formed in the upper side of the motion plate. The left-hand end of the lock bar 29 (Fig. 2) cooperates with a notch 34 provided in a lock rod 35 which is secured to the front rod 5 . The parts are so proportioned that when and only when the switch occupies its full normal position, the notch 34 will be aligned with the lock bar, and when the motion plate 11 is in its extreme left-hand position, the lock bar will enter the notch 34 as shown in Fig. 2 to lock the switch in its normal position.

The operation of the portion of the apparatus thus far described will be apparent to those versed in the art. When the hand-throw lever is rotated to the normal position illustrated in the drawings, the motion plate 11 is moved to its extreme left-

hand position as illustrated in Fig. 2. The switch points are held in the position illustrated in Fig. 1 by engagement of the roller 21 with the cam surface of the escapement crank 22 , the lock bar 29 entering the notch 34 of the lock rod 35 to lock the switch points in their normal position. To reverse the switch, the hand-throw lever 20 is rotated in a counterclockwise direction approximately 180° from its one extreme position to the other. Segment gear 15 will be rotated by the hand-throw lever to move the motion plate 11 to its extreme right-hand position. The initial movement of the motion plate will withdraw the lock bar 29 from the notch 34 in the lock rod 35 to unlock the switch, the continued motion of the motion plate causing the escapement crank to be rotated by engagement of the roller 21 and the cam surface carried by said crank, the crank in turn rotating the switch actuating shaft 23 to rotate the switch operating arm 27 to move the throw rod 7 causing the switch points 2 and $2a$ to move to their reverse position. To restore the switch to its normal position, the operation of the parts is exactly the reverse of that described.

The switch and lock movement B also includes a circuit controller for controlling the signals governing traffic movement over the switch A. The circuit controller comprises a rocker arm 36 pivotally supported intermediate its ends on a pin $37a$ secured within a pair of spaced upstanding lugs 37 provided on the frame 32 . The rocker arm 36 is disposed directly above the lock bar 29 , and is provided with a cam face $36a$ (Fig. 6) which cooperates with a cam face $38a$ provided on a cam dog 38 (Fig. 2) secured to the upper surface of the lock bar 29 in such a manner that when the lock bar is moved to the position in which it is withdrawn from notch 34 in the lock rod 35 , the cam face $38a$ will engage the cam face $36a$ shortly before the lock bar has cleared the notch. The rocker arm 36 will thus be rotated in a counterclockwise direction (Fig. 2) from its normal position illustrated to its extreme reverse position. The rocker arm 36 is further provided with a cam face $36b$ which joins the right-hand end of the cam face $36a$. The cam face $36b$ cooperates with the top of the cam dog 38 to maintain the rocker arm 36 in its extreme reverse position whenever the switch is unlocked.

A contact operating member 39 (see Fig. 3) is pivotally attached to the left-hand end of the rocker arm 36 , and is guided to move vertically by means of upwardly extending studs 40 which are provided on the frame 32 , and which pass freely through clearance holes formed in the contact operating member. Surrounding the studs between the frame and the contact operating member are compressed coil springs 41 , whereby the operating member is biased to an upper position in which it engages adjustable stop nuts 42 screwed onto the upper ends of the studs, it being noted that since the contact operating member is pivotally attached to the rocker arm 36 , the springs 41 also serve to bias the rocker arm to its normal position in which it is shown in Fig. 2. Two superimposed insulating blocks 43 and 44 are secured to the upper side of the operating member, and extending between these blocks are the free ends of a plurality of flexible contact fingers 45 , here shown as four in number. Each contact finger 45 cooperates with a fixed contact member 46 to form a contact $45-46$. Each contact finger 45 and the associated contact member 46 are clamped to the opposite sides of an insulating block 47 by means of terminal posts

48 and the insulating block 47, in turn, is supported on lugs 49 projecting upwardly from the frame 32. The parts are so proportioned that when the rocker arm 36 occupies its normal extreme position in which it is shown in the drawing, each contact 45-46 will be open, but when the rocker arm is rotated to its other extreme position, each contact 45-46 will then be closed. It will be apparent, therefore, that the contacts 45-46 will become closed whenever the lock bar 29 is withdrawn from the notch 34 in the lock rod 35 to unlock the switch.

The circuit controller also comprises a point detector lever 50 (Figs. 2, 3, and 4) which is pivotally supported on a pin 51 mounted in the frame 32. An anti-rattler spring 52 is interposed between the frame and a laterally projecting latch arm 53 on the point detector lever tending to bias the point detector lever in a counterclockwise direction to the position in which a roller 54 mounted in a depending lug 55 formed on the point detector lever enters a notch 56 in a point detector rod 57. The point detector rod 57 is slidably mounted in the casing 9, and as shown in Fig. 1 is attached, by means of a link 58 and a bolt 59 to the movable rail 2 of the switch A in the usual and well-known manner. The point detector lever 50 is also provided with a laterally projecting arm 60 having a rounded end 61 which overlies and cooperates with the conical head 62 of a finger 63 which is adjustably mounted in an upstanding lug 64 provided on the rocker arm 36. The springs 41 biasing the rocker arm 36 in a clockwise direction also provide the major biasing force for maintaining the roller 54 in the point detector rod notch 56 through the co-operation of the conical head 62 of the finger 63 mounted on the rocker arm and the rounded end 61 of the point detector lever arm 60.

The notch 56 in the point detector rod 57 is so disposed and the parts are so proportioned that the roller 54 will enter the notch 56 when and only when the movable rails 2 and 2a of the switch A occupy their normal extreme positions and the movable rail 2 is in proper engagement with the fixed rail 1. The parts are further so proportioned that when the roller 54 is within the notch 56 and the rocker arm 36 occupies its normal position, the rounded end 61 of the point detector lever will engage the upper side of the conical head 62 of the finger 63, but when the roller 54 is forced out of the notch 56, the resultant clockwise rotation of the point detector lever will cause the rounded end 61 of the point detector lever to cooperate with the head 62 of the finger 63 to rotate the rocker arm 36 to its reverse extreme position, thus causing the contacts 45-46 to become closed. It follows, therefore, that any displacement of the switch point 2 away from the rail 1 in excess of the normal safe distance when the parts are in the positions shown in the drawings will operate the contacts.

As pointed out in the aforesaid patent, the contacts of a circuit controller are utilized to control signals governing traffic over the associated switch. Their primary purpose is to cause the signals to indicate "stop" unless the switch points occupy their proper positions relative to the fixed rails and are properly locked in these positions. If a train improperly trails the switch while it is locked in its normal position, the switch points will be displaced an amount which will operate the point detector contacts of the circuit controller by movement of the point detector rod. In order to detect the trailed condition of the switch, a

latching mechanism was provided in the aforesaid patent which retained the circuit controller contacts in their closed positions until they were subsequently released by a maintainer. The signals governing traffic over the switch thus continued to display a restrictive indication until the maintainer released the contacts of the circuit controller and permitted them to return to their normal positions. While the latching mechanism described in the aforesaid patent worked satisfactorily in retaining the circuit controller contacts in their closed positions when the switch was trailed, false latchouts occurred occasionally in installations subjected to excessive vibrations. I have accordingly provided a novel latching mechanism which will eliminate these false latchouts.

The novel latching mechanism embodying my invention comprises the previously referred to latch arm 53, the free end of which is provided with a latch dog 65 having a rounded end or camming surface 65a cooperating with a latch catch 66. The latch catch is provided with a screw threaded upper portion 67 adjustably screwed through a tapped hole in an extending arm 68 of a U-shaped latching member 69 pivotally supported at its ends on a rod 70 mounted in the upstanding lugs 71 on the frame 32. The latch catch 66 is locked in its desired position on the latching member arm 68 by means of a lock washer 72 and a jam nut 73 provided on the threaded portion 67 above said arm. The latch catch (Fig. 5) is formed with parallel sides 74 terminating at the lower edges in outwardly extending sides or cam faces 75. The cam faces 75 in turn terminate in two sides or cam faces 76 with a slope approximately equal but opposite in sign to the slope of the cam faces 75. The cam faces 76 terminate in two sides 77, hereinafter referred to as shoulders 77. The shoulders 77 are angularly disposed to a slight extent with the parallel sides 78 on the lower end of the latch catch 66.

The U-shaped latching member 69 pivoted on the rod 70 is provided with a cam arm 80 extending toward the right (Figs. 2, 4 and 6), the lower end of the arm being provided with a cam face 80a which cooperates under certain conditions hereinafter described with the cam dog 38 carried by the lock bar 29. The latching member 69 is biased to rotate in a clockwise direction (Fig. 2) by the cam arm 80 and by a spring 81 which is connected at one end to a projecting lug 82 on the frame 32 and at the other end to a spring arm 83 provided on the latching member.

The parts of the latching mechanism described are so proportioned and the latch catch 66 is so adjusted that when the roller 54 on the point detector lever 50 is within the notch 56 of the point detector rod 57 and the lock bar 29 is in its locking position in which the left-hand end of the bar is within the notch 34 of the lock rod 35 as shown in the drawings, the point of juncture of the sides 74 and 75 of the latch catch 66 will engage the rounded end 65a of the latch dog 65 on the point detector lever 50. The latching member 69 will thus be prevented from rotating in a clockwise direction (Fig. 2) about the rod 70 by the spring 81 and the cam arm 80.

Assuming the switch A to be in its normal position as illustrated in Fig. 1 and the switch is moved to its reversed position by means of the hand-throw lever 20 in the manner described, the movement of the lock bar 29 in withdraw-

ing from the notch 34 in the lock rod 35 will cause the cam face 38a of the cam dog 38 to engage the cam face of the cam arm 80 to rotate the latching member 69 in a counterclockwise direction against the bias of the spring 81. The latch catch 66 will accordingly be rotated in the same direction to a position out of engagement with the latch dog 65. The cam face 38a will also engage the cam face 36a on the rocker arm 36 and rotate the rocker arm from the normal extreme position illustrated to its reverse extreme position to close the contacts 45-46. The motion of the rocker arm 36 also lowers the finger 63 to such a position that when the switch points subsequently start to move and force the roller 54 out of the notch 56 in the point detector rod 57, the point detector lever 50 will be free to rotate without causing the rounded end 61 of the arm 60 of the point detector lever to engage the conical head 62 of the finger. The continued motion of the lock bar 29 after the roller 54 is forced out of the notch 56 in the point detector rod 57 will cause the cam dog 38 to move past the cam face 80a of the cam arm to permit the latching member 69 to rotate in a clockwise direction (Fig. 2) to the position in which the cam arm 80 engages the lugs 37 which support the pin 37a, but the dog 38 will continue to engage the rocker arm cam face 36b during the remainder of the movement of the lock bar. The rocker arm will thus be retained in its reverse extreme position.

When the hand-throw lever 20 is operated to restore the switch to the normal position illustrated in Fig. 1, the operation of the circuit controller will be substantially the reverse of that just described. The latching member 69 will be rotated to the position in which the latch catch 66 is clear of the latch dog 65 due to the engagement of the cam surface 38b provided on the cam dog 38 with the cam surface 80a on the cam arm 80. The latch catch will be retained in this position until after the notch 56 of the point detector rod moves into alignment with the roller 54 by the engagement of the top of the cam dog 38 with the cam surface 80a. Inasmuch as the operation of the circuit controller during movement of the switch points to their normal positions is substantially the reverse of that which has been described in connection with the movement of the switch points to their reverse positions, it is believed that the operation of the circuit controller during this return movement will be understood from an inspection of the drawings and from the foregoing description.

Assuming now that the switch A is in the normal position illustrated in Fig. 1 and that the parts are in the positions shown in the drawings and that a train trails the switch. Under these conditions, the trailing train will move the switch point 2 away from stock rail 1 to move the point detector rod 57 to the left as seen in Fig. 3. The roller 54 will be forced out of the notch 56 causing the point detector lever 50 to rotate in a clockwise direction (Figs. 2 and 6). The clockwise rotation of the point detector lever will act through the arm 60 and finger 63 to rotate the rocker arm 36 in a counterclockwise direction about its pivot 37a to its extreme reverse position to close the contacts 45-46.

The rotation of the point detector lever 50 will also move the latch arm 53 downwardly to move the latch dog 65 downwardly. The downward

movement of the latch dog will cam the latch catch 66 in a counterclockwise direction while in engagement with the sides 75 of the catch. The continued downward movement of the latch dog past the sides 76 of the latch catch will permit clockwise rotation of the latch catch due to the influence of the spring 81; the top surface 65b of latch dog engaging the shoulder 77 when the latch dog has been moved to its extreme downward position. The point detector lever 50 will be held in a position in which the roller 54 is out of the notch 56 of the point detector rod and the rocker arm 36 will be held in its extreme reverse position by the arm 60 and finger 63. The contacts 45-46 will thus be held closed until the latching mechanism is restored to its unlatched position.

To release the contact operating member and permit the contacts 45-46 to open after they have been closed in the manner described, the cover 10 of the casing may be removed and the cam arm 80 raised, the spring 52 returning the point detector lever 50 and consequently the latch dog 65 to their normal positions, providing of course that the roller 54 of the point detector lever enters the point detector rod notch 56. The contacts 45-46 may also be opened by operating the switch movement to its reverse position, the cam dog 38 raising the cam arm 80 to release the latch catch. Should the switch points be damaged and the switch movement subsequently operated to its normal position, the roller 54 on the point detector lever will not enter the point detector rod notch 56 due to the damaged switch points.

From the foregoing description of the latching mechanism and its operation it is evident that the novel mechanism provided will hold the point detector lever 50 in its extreme reverse position when the switch A is trailed. My novel latching mechanism is further characterized by the fact that false latchouts due to excessive vibration and shock are eliminated. As is well known in the railroad art, the pounding of the wheels over the rails set up vibration which can and does affect equipment connected with or installed adjacent to the rails. In the case of switches, the pounding on the rails is transmitted through the point detector rod to the point detector lever. The suddenly applied shock along the axis of the point detector rod transmitted through the roller of the point detector lever tended to rotate the point detector lever and its associated latch arm and latch dog.

In the latching mechanism herein provided the problem presented by false latchouts is eliminated by providing firstly, a spring (41) for biasing the point detector lever whose natural frequency of operation is different than the shock frequency set up by the rails, and secondly, by providing the latch catch with camming surfaces which are engaged by the latch dog of the latch arm, the camming surfaces being such that the latch catch is kicked out of the way for a sufficient period of time by the movement of the latch dog to allow the latch dog to return to its initial position.

Referring to Fig. 5 in which the latching mechanism is shown in its normal or unlatched position, it will be noted that the rounded tip end 65a of the latch dog 65 engages the surfaces 74 and 75. The downward movement of the latch dog will throw the latch catch 66 in a counterclockwise direction about its pivot 70 away from the latch dog. In the case of a trailed switch,

the roller 54 engages the point detector rod 57 so that the latch dog is held in its latching position. The return of the latch catch to its latching position will permit the top surface 65b of the latch dog to catch under the shoulder 77 to latch out the mechanism. Now, should the latch dog 65 be displaced in a downward direction, as in the case of shock loads applied to the point detector rod, the camming action of the latch dog end 65a and surface 75 will throw the latch catch to the right in a counterclockwise direction about its pivot. The latch dog will return to its unlatched position under the influence of springs 41 and to some extent spring 52, the roller 54 reentering the point detector rod notch 56. The angular displacement of the latch catch will permit the latch dog 65 to return to its unlatched position before the latch catch 66 returns to its normal position, thereby preventing the mechanism from latching up. It will be appreciated from the drawing that the latch dog 65 need not return to its extreme normal position illustrated before the return of the latch catch. Should the latch catch recover from its throw so that the latch catch surface 76 engages the latch dog end 65a, the latch dog will be returned to its extreme normal position by the spring 41 which is stronger than the return spring 81 for the latch catch.

In Fig. 6 I have illustrated a second embodiment of my invention in which a latch catch 84 is provided having a screw threaded upper portion 85 adjustably screwed through the tapped hole in the extending arm 68 of the latching member 69. The latch catch 84 is formed with two outwardly and downwardly sloping sides 86 terminating in a shoulder 87.

The operation of the latching mechanism illustrated in Fig. 6 is similar to that shown in Fig. 5. Downward movement of the latch dog 65 will throw the latch catch in a counterclockwise direction in the manner heretofore described. In the case of a trailed switch, the top surface 65b of the latch dog will engage the shoulder 87 of the latch catch to latch up the mechanism. In the case where shock loads are transmitted through the point detector rod, the downward movement of the latch dog will throw the latch catch to the right out of the way a sufficient length of time to permit the latch dog to return from its latching position, thereby preventing false latchouts.

It will be appreciated from the foregoing that I have provided a novel latching arrangement for switch and lock movements by which the circuit controller contacts of the movement are held in their restrictive signal position when the switch is trailed and which prevents false latchouts of the circuit controller contacts in installations of the movement where excessive vibration and pounding prevail.

Although I have herein shown and described only two forms of a latching mechanism for a switch and lock movement embodying my invention, it is understood that various changes and modifications may be made therein within the scope of the appended claims without departing from the spirit and scope of my invention.

Having thus described my invention, what I claim is:

1. A latching mechanism comprising a pivoted latch dog biased in a first direction to an unlatched position and adapted to be moved in an opposite direction and held in a latching position, a pivoted latch catch having at least one cam surface and a shoulder, and biased in an opposite direction toward a latching position, said

cam surface engaging said latch dog when said latch dog is in its unlatched position, said latch dog moving in said opposite direction toward its latching position camming said latch catch in said first direction away from said latch dog, said latch dog engaging the shoulder of said latch catch only when said latch dog is held in its latching position.

2. A latching mechanism comprising a pivoted latch dog biased in a first direction to an unlatched position and adapted to be moved in an opposite direction and held in a latching position, a pivoted latch catch having first and second cam surfaces with slopes of opposite signs and a shoulder, and biased in an opposite direction toward a latched position so that said first cam surface engages said latch dog when said latch dog is in its unlatched position; said latch dog moving in said opposite direction toward its latching position sliding over said first cam surface of said latch catch and camming said latch catch in said first direction away from said latch dog, said latch dog engaging said shoulder of said latch catch only when said latch dog is held in its latching position, said second cam surface of said latch catch permitting the latch dog moving in said first direction from its latching position to slide over said second cam surface and then over said first cam surface to return to its unlatched position.

3. In a switch operating mechanism for a railway switch having means for moving the movable rails of said switch between an extreme normal position and an extreme reverse position and locking said movable rails in an extreme position, a point detector rod secured to said movable rails and provided with a notch, a pivoted point detector lever provided with a roller biased to engage said point detector rod and to enter the point detector rod notch when and only when said switch is locked in an extreme position, and a contact operating member held in an operative position when said roller is forced out of the point detector rod notch, the combination of a latching member movable with said point detector lever, a pivoted latch member biased to a latching position, said latching member throwing said latch member away from the latching member when said roller is forced out of the point detector rod notch and held upon the return of said latch member to its latching position by said latch member when said roller engages the point detector rod to hold said contact operating member in its operative position, suddenly applied longitudinal loads on said point detector rod causing said latching member to throw said latch member away from said latching member a period of time sufficient to permit the latching member to return to its initial position before said latch member returns to its latching position.

4. In a switch operating mechanism for a railway switch having means for moving the movable rails of said switch between an extreme normal position and an extreme reverse position and locking said movable rails in an extreme position, a point detector rod secured to said movable rails and provided with a notch, a pivoted point detector lever provided with a roller biased to engage said point detector rod and to enter the point detector rod notch when and only when said switch is locked in an extreme position, and a contact operating member held in an operative position when said roller is forced out of the point detector rod notch, the combination of a latch

11

dog movable with said point detector lever, a pivoted latch catch having at least one cam surface and a shoulder, and biased to a latching position so that said cam surface engages said latch dog; said latch dog camming said latch catch away from said latch dog when said roller is forced out of the point detector rod notch and engaging said shoulder upon the return of said latch catch to its latching position. when said roller engages said point detector rod to hold said latch dog and latch catch in a latched condition and to hold said contact operating member in its operative position, suddenly applied longitudinal loads on said point detector rod causing said latch dog to cam said latch catch away from said latch dog a period of time sufficient to permit the latch dog to return to its initial position before said latch catch returns to its latching position.

5. In a switch operating mechanism for a railway switch having means for moving the movable rails of said switch between an extreme normal position and an extreme reverse position and locking said movable rails in an extreme position, a point detector rod secured to said movable rails and provided with a notch, a pivoted point detector lever provided with a roller biased to engage said point detector rod and to enter the point detector rod notch when and only when said switch is locked in an extreme position, and a contact operating member held in an operative position when said roller is forced out of the point detector rod notch, the combination of a

12

latch dog movable with said point detector lever, a pivoted latch catch having first and second cam surfaces with slopes of opposite signs and a shoulder, and biased to a latching position so that said first cam surface engages said latch dog; said latch dog camming said latch catch away from said latch dog when said roller is forced out of said point detector rod notch and engaging said shoulder upon the return of said latch catch to its latching position when said roller engages said point detector rod to hold said latch dog and latch catch in a latched condition and to hold said contact operating member in its operative position, suddenly applied longitudinal loads on the point detector rod causing said latch dog to cam said latch catch away from said latch dog a period of time sufficient to permit said latch dog to return to its initial position before said latch catch returns to its latching position, said second cam surface being such to permit said latch dog to slide thereover in its return to its initial position should the second cam surface engage the latch dog.
